ATTY'S

UNITED STATES PATENT OFFICE

HARLEY O. POTTER, OF PEORIA, ILLINOIS

GOLF GLOVE

Application filed January 12, 1931. Serial No. 508,039.

This invention relates to golf gloves.

One of the objects of the invention lies in the provision of a glove particularly adapted for the protection of the player's hands while playing golf.

Another object lies in the provision of a golf glove adapted to protect the hands of a player, said glove being fashioned in such manner as not only to permit playing of the game in an unrestricted manner, but also because of its form, to assist the player in so doing by insuring a proper alignment of the club held in the player's grasp.

A further object lies in the provision of a glove particularly fashioned for use in playing golf, the same primarily functioning to protect the player's hands from cold, while at the same time in no way restricting the proper grasp of the club and also being formed in such a manner as to assist the player by defining the proper angle of support of the club within the player's grasp.

A still further object lies in the provision of a golf glove so fashioned as to protect the wrist and back of the player's hands, while at the same time offering no restriction whatsoever to the proper grasp of the club in the palms of the player's hands, the glove being so constructed as to insure comfortable but fixed securement upon the hands of the player.

Other objects will appear in the following specification taken in connection with the annexed drawing, in which—

35 Fig. 1 is a perspective view showing the glove with the fingers of the player's hand in an extended position; and

40 Fig. 2 is a perspective view showing the glove with the player's fingers grasping the club.

Before referring specifically to the drawing for a detailed description of applicant's golf glove, it is thought best first to summarize the advantages of such a glove when considered in the light of such a great and growing popular pastime.

45 The game of golf has grown in popularity in such a rapid manner and has become so well known as to negative any necessity of 50 describing in detail either the manner of play

or the physical and health advantages gained therefrom.

The game, although normally played in seasons which negative the use of any protecting means for the hands, nevertheless also and in an increasing manner has found favor even during climatic conditions when the player, both from choice and from necessity, requires a certain amount of protection for his hands.

Obviously, a game requiring such an extremely fine sense of timing and such a great amount of co-ordination, negatives the use of any covering for the hand which would interfere in any way with the movement of the player's fingers or palm. In other words, it is admitted that the game, to be played properly, must permit a grasp of the club with the player's open palms and with no possible restriction to the movement of the fingers. It is admitted that under certain circumstances, especially during the play by novices, that gloves are sometimes worn for the prevention of blisters, callouses and the like, but in the present instance the glove later to be described is designed primarily as a protection from climatic conditions and also, as will be later brought out, as a guide to the player respecting the proper alignment of the club grip within the player's grasp.

It will further be noted, when the glove has been described in detail, that although same is fitted in a comfortable and secure manner upon the player's hand, nevertheless same is so arranged as to prevent any disadvantageous contact of the glove protecting surface during the player's grasp of the club grip.

Now, referring specifically to the drawing, there is displayed in the various views, which include perspective showings, applicant's golf glove. This glove may be constructed either of a soft flexible leather or synthetic composition as well as of knitted wool. The glove is designed primarily, of course, to protect the wrist and back of the player's hand, without interfering, as previously stated, with proper play, in that the palm is left open, and the fingers not only uncovered but absolutely free for movement which is necessary in the proper playing of the game.

The glove comprises a wrist portion 10, adapted as shown to entirely surround the wrist in a protective and close-fitting manner. The back of the glove is described at 11 and 5 it is also apparent that the same covers the entire exposed surface of that portion of the player's hand in a close-fitting and comfortable manner.

The manner of securing the glove to the 10 fingers is shown to be by a plurality of extremely narrow attachment strips shown at 12, which are, as is readily apparent, merely securing loops through which the player's fingers project. It will also be noted that 15 these loops secure the glove on the line upon which the fingers are bent or crooked with respect to the palm during the natural and normal grasping of the club. As a matter of fact, these loops, although sufficient to insure 20 proper securing of the glove, nevertheless are so narrow as to disappear within the crease that is formed when the fingers are bent with respect to the palm, during the player's grasp of the club grip. By arranging 25 these loops in such manner and by forming them of a soft, flexible material, they interfere in no way with the proper grasp of the club, and as a matter of fact do not come in substantial contact with any portion of 30 the club grip.

As stated before, the palm of the glove is left entirely open, although there is obviously a connection between the closed wrist portion and the back and protecting portion of 35 the glove. The wrist portion is connected to the back in one instance upon one side on a line 13, which angle of connection is rather immaterial and is important only in that no portion of the glove comes in contact with 40 the club grip when held in playing position.

However, the manner of securing the glove to the thumb portion is not only important but novel. It will be noted in the drawing that the glove comprises a covering for a portion of the thumb surface and particularly the upper side of the thumb, this in order to insure not only protection for the back of the hand but also the thumb portion which comprises a substantial part of the hand. 45 The glove covering actually surrounds the base of the thumb in the manner shown at 14 in the drawing. However, attention is called to the angle assumed by the glove with respect to the palm, not only in the connection 50 of the wrist portion with the back of the hand at this point but also with respect to the material that lies upon the inner side of the thumb.

The connecting line which is described at 60 15 between the wrist and back of the hand upon the thumb side of the glove is not only substantially straight, but angles laterally in such manner that but a very small amount of glove material lies between the palm of the hand and the thumb. As a matter of fact, 65

this material is sufficient merely to insure comfortable securing of the glove upon the hand, although it accomplishes still another result in that it defines the proper angle, or it may be said alignment, of the club grip 70 in the palm of the player's hand. In other words, the line 15 has importance from all angles, first as a means of securing the glove in a comfortable and protective manner upon the hand and also satisfactorily surrounding the thumb as well as additionally operating 75 as a means, from an instructional standpoint, of insuring the grasp of the club in a proper manner. The glove is so designed as to permit grasp of the club grip in a natural and proper position without restriction in any 80 way to the player. However, should the club be grasped in an unnatural and improper manner, it is quite possible that the glove covering adjacent the line 15 would interfere 85 with the proper play, inasmuch as said portion would become wedged between the palm of the hand and the glove.

It may be definitely stated that the glove is so designed as to practically force the 90 player to a proper holding of the club grip.

It will be noted from the drawing that when the player, wearing a pair of the gloves herein described, grasps the club grip, the angle assumed by the glove lines 15 will be 95 parallel to the line of the club grip and thus the player may be instructed in the proper grasp of the club, either by actual placement of the club grip in such parallel relationship with the line 15 when grasping the club, or by necessity when finding a portion of the glove preventing unrestricted clasp or grasping of the club in the preliminary club movements prior to the actual swing.

Applicant realizes that protective means have been afforded for the hands of persons in many instances and for various purposes. However, the present glove, although designed obviously as a protecting means, nevertheless in its make-up includes such structural formations as to render its construction extremely technical, looking towards the production of a protective means that does not interfere in any way with the player's game, either by mentally or physically distracting him, because of a restriction of his otherwise normal physical grasp of the club grip. It is believed that applicant's glove, because of its great regard for structural detail, has advantages that accrue to no other character of covering that has heretofore been developed as a protective means for golfer's hands, and this especially in view of the particular fashioning of the glove at points adjacent to and surrounding the palm, including the narrow loops which, as previously described, substantially disappear in the crease formed adjacent thereto when the club is 105 grasped.

What I claim is:

1. A golf glove comprising a portion adapted to cover the back of the hand and terminating at the base of the fingers, means for 5 securing said back portion to the fingers, a wrist encircling portion secured to the back portion, and a portion secured to said wrist portion on the palm side thereof and covering the base of the thumb, the upper edge of 10 said last named portion extending from the butt of the hand on the side opposite the thumb to the space between the thumb and first finger, the remainder of the palm above 15 said edge being uncovered, said edge serving to indicate the proper angle at which a golf club should be held.
2. A golf glove comprising a portion adapted to cover the back of the hand and terminating at the base of the fingers, means 20

for securing said back portion to the fingers, a wrist encircling portion secured to the back portion, and a portion secured to said wrist portion on the palm side thereof and covering the base of the thumb, the upper edge of 10 said last named portion extending from the butt of the hand on the side opposite the thumb to the space between the thumb and first finger, the remainder of the palm above 15 said edge being uncovered, said edge serving to indicate the proper angle at which a golf club should be held, said securing means comprising thin loops of a size small enough to 20 disappear in the creases at the bases of the fingers when the fingers are bent.

In testimony whereof I have hereunto affixed my signature.

HARLEY O. POTTER.
